Inventor

D. D. BAILEY

By Watson E. Coleman

Attorney

UNITED STATES PATENT OFFICE.

DAVID D. BAILEY, OF COFFEYVILLE, KANSAS.

NECKTIE.

1,226,741.

Specification of Letters Patent. Patented May 22, 1917.

Application filed January 13, 1917. Serial No. 142,249.

To all whom it may concern:

Be it known that I, DAVID D. BAILEY, a citizen of the United States, residing at Coffeyville, in the county of Montgomery and State of Kansas, have invented certain new and useful Improvements in Neckties, of which the following is a specification, reference being had to the accompanying drawings.

10 This invention comprehends certain new and useful improvements in wearing apparel and relates particularly to neckwear.

The invention has for its primary object to provide an improved article of this character which combines, in a very simple and effective manner, a combination of parts whereby the cravat may be worn as the ordinary ascot, four-in-hand, or bow-tie, or a part of it worn by itself as the ordinary string or bow-tie, and which possesses the additional advantages of making a new tie or cravat out of an old one by cutting off the end of the old tie and attaching one of my improved tie-ends to it.

25 And the invention also aims to generally improve devices of this character so as to render them more useful and commercially desirable.

With these and other objects in view as 30 will more fully appear as the description proceeds, the invention consists in certain constructions, arrangements and combinations of parts that I shall hereinafter describe.

35 For a full understanding of the invention, reference is to be had to the following description and accompanying drawing, in which—

Figure 1 is a perspective view showing one 40 form of my improved necktie, the parts being separated and in juxtaposition to each other,

Fig. 2 is a similar view but with the parts in assembled relation,

45 Figs. 3 and 4 are fragmentary sectional views showing the arrangement of the fasteners.

Corresponding and like parts are referred to in the following description and designated in all of the views of the accompanying drawing by like reference characters.

My improved combination tie or cravat comprises a tie-end 1 and a string or bow-tie 2. The tie-end 1 is formed at one end with 55 a sheath or casing 3, which is preferably unpadded and designed to receive one end

of the string or bow-tie 2, separable fasteners 4 of any desired shape or design being secured to the tie-end 1 at the end of the sheath 3 and to the string or bow-tie 2 at suitable distances from one end thereof, this being the end which is inserted into the sheath. 60

Preferably I employ two separable fasteners for each tie or cravat, the complementary or mating members of the fasteners 65 being connected to the opposite sides of the sheath 3 and bow-tie 2, and near the side edges thereof so as to avoid any bulky effect.

From this description in connection with 70 the accompanying drawing, the operation and advantages of my improved combination tie or cravat will be apparent. The device may be used in three ways. For example, when one end of the string or bow-tie 2 is inserted into the sheath 3 and the parts connected together by the separable fasteners 4, a regular four-in-hand, ascot, or bow-tie is produced, and one which will not 75 only be as strong and durable as the ordinary tie, but one which, when worn, cannot be told from the ordinary tie. By taking off the tie-end 1 there remains an ordinary string or bow-tie, just as it comes from the store, with the exception, of course, of the 80 fastening members, but these will not be in the way when the part 2 is worn. Furthermore, the invention may be employed in making a new tie out of an old one by cutting off the end of the old tie and attaching 85 one of my tie-ends 1.

It will also be seen that the tie-end 1 itself possesses several advantages. In the first place, it is two ties in one, thereby saving material; the tie-end eliminates the necessity 90 of padding the four-in-hand tie for the reason that the bow-tie 2 acts as padding for the four-in-hand when the parts are joined; and the two parts may be of the same material or of different materials or designs and 95 any end can be used on any bow-tie without detection from the outside when the device is worn. 100

While the accompanying drawing illustrates what I believe to be the preferred embodiment of my invention, it is to be understood that the invention is not limited thereto but that various changes may be made in the construction, arrangements and proportions of the parts without departing 105 from the scope of the invention as claimed. 110

What is claimed, is:

As a new article of manufacture, the herein described cravat, comprising a tie-end provided at one end with a sheath, and a complete string tie insertible at one end in 5 said sheath, the sheath being unpadded, and separable fasteners attached to said sheath at one end thereof and the string tie at a distance from one end of the latter, whereby that portion of the string tie between said

fasteners and the adjacent end of the string tie, lying within the sheath, will constitute a padding for the tie-end.

In testimony whereof I hereunto affix my signature in the presence of two witnesses.

DAVID D. BAILEY.
